UNITED STATES PATENT OFFICE.

DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY.

METHOD AND APPARATUS FOR EQUALIZING CONCENTRATION IN BOILER DRUMS.

Application filed February 28, 1920, Serial No. 362,005. Renewed March 18, 1925.

In steam boilers employing a plurality of drums through which the water circulates, particularly when, as is usual, the boiler is made up of a series of tubes in sets, each set associated with one of the drums and substantially independent of the other drums, there sometimes occurs under certain conditions of operation an unequal concentration of solids in the different drums. This produces different operating characteristics in the respective sections of the boiler which, obviously, is undesirable.

One of the objects of my invention is to provide a method and means by which the water circulating in each section of a boiler may be mingled with the water circulating in another section, so that there will be a balancing of the concentration of solids in the respective sections, thus causing each section to operate in substantially the same manner as the other sections, no matter how long the boiler has been in operation.

With this and other objects in view, my invention consists of the method and apparatus herein described and more specifically pointed out in the appended claims.

In the drawings, Figure 1 is a sectional side elevation of one form of boiler embodying my invention; Fig. 2 is an enlarged rear elevation of a portion of Fig. 1 with the lower part cut on the section line 2—2 of Fig. 3; Fig. 3 is a side view of a portion of Fig. 2 with some of the parts broken away; Fig. 4 is a plan view and Fig. 5 a sectional elevation on the line 5—5 of Fig. 4 of a modification of my invention, and Fig. 6 is a plan and Fig. 7 is a sectional elevation on line 7—7 of Fig. 6, of another modification of my invention. Like reference characters indicate like parts in the several views.

In Fig. 1, I have chosen for purposes of illustration, a boiler of the Babcock & Wilcox type having a set of water tubes 10, each vertical row of which is expanded into a vertical downtake header 11 and a vertical uptake header 12. Each downtake header has a nipple 13 connecting the top of the header with one of the upper longitudinal drums 14, 15 and 16, and each uptake header 12 has a nipple 17 connecting it with one of the longitudinal drums 14, 15 and 16 at the front end thereof. In the form shown, each of the drums is provided with a cross box so that the nipples 13 and 17 will be parallel

to each other but, obviously, any other form of connection between the nipples and the drums may be used.

The upper drums are provided with the usual splash plates 18 fitted above the top of the uptake headers 12 and the feed water for the boiler enters the front end of each of the longitudinal drums 14, 15 and 16 through the pipe 19.

In the normal construction of the boiler, it will be noted that each drum has associated with it a certain number of the tubes 10 and of the downtake and uptake headers 11 and 12, together with the nipples 13 and 17 connecting the respective headers with the drums. The water in each section will circulate by passing upwardly through the headers 12 into the drum and thence rearwardly to the nipples 13, down which it passes to the headers 11 and then again to the tubes 10. As will be seen by an inspection of Figure 2, if the arrangement of the bent pipes, therein shown, is disregarded, each section is entirely independent of the other sections, so far as the water circulation due to the heating and evaporating action, is concerned. Consequently, if for any reason there is greater evaporation in one section than in another, any solids in the water will become more and more concentrated in that section with the arrangement of such boilers as have heretofore been made.

Unequal concentration in the sections may also arise from supplying more feed water to one of the sections than to the others.

There is a connection between the circulation of the section which is secured through the mud drum 111 of the boiler. As is well understood, the feed water is supplied to each of three of the drums, one of the feed water connections which enter the front heads of the drums above the uptake headers being shown at 161 in Fig. 1. Should more feed water be fed to one drum than to the others, the water will flow from the drum receiving the most feed water and its attached sections through the mud drum 111 to the other drums and their sections. The drum in which the greatest amount of feed water enters, if, together with its sections, it is subjected to no greater degree of heat than the other drums and their sections, will eventually contain water at a lower degree of concentration than the other drums with their sections. This presup-

poses that the amount of water blown off from each drum with its sections through the blow-off valves marked 162 in Fig. 1 is the same in each case, a blow-off valve 5 being provided for each drum with its sections. I overcome any unequal concentration in the several sections by diverting some of the water circulating in one of the sections so as to cause it to flow into another of 10 the sections, and by thus interconnecting the several sections, I equalize the concentration therein, this concentration being most apparent where the sections are not interconnected, in the drums in which the largest 15 quantity of the water is evaporated in proportion to the amount of the water fed to the drum.

The means shown in Figures 1, 2 and 3 represents one simple manner of carrying 20 out my invention. In this form, the two end downtake nipples of adjacent sections are curved, so that the nipple connected with one drum connects with a header, which, in normal construction, would be 25 connected with an adjacent drum. This change is made in each end nipple of adjacent sections. For instance, the nipple 132 connects the drum 14 with a header, the tubes 10 of which, at the opposite end, connect 30 with an uptake header 12 through which the water passes through the nipple 17 to the drum 15. Similarly, the nipple 133 connects the drum 15 with a downtake header, the tubes 10 of which, are connected 35 with an uptake header 12 through the nipple 17 with the drum 14. It will thus be seen that, in the construction illustrated, some of the water which is circulating 40 through the drum 14 is carried rearwardly into the drum 15, and similarly, water from drum 15 is carried into drums 14 and 16 and so on, and this is done without disturbing the normal circulation in the several sections.

45 Instead of using the nipples such as 132, 133, as a means for diverting the water from one section to another, I may employ the arrangement shown in Figures 4, 5, 6 and 7 in which connecting pipes are placed 50 between the drums.

In Figures 4 and 5, a pipe 20 connects the drums 14 and 15, so as to lead water from the front of the drum 14 to the rear of the drum 15. Similarly, a pipe 21 connects the drums 14 and 15. Each of the pipes 20, 21 has one end located within one of the drums 14, 15 beneath the splash plate 18 and below the water level in the drum. Since, in the form of boiler shown in Figure 1, the circulation of the water in the drums is from the front to the rear, consequently, some of the water in each of the drums 14, 15 will pass into the pipes 20, 21 and will be carried to the rear of the opposite drum to there enter the circulation

in that drum. In case the concentration becomes higher in one drum than in the other, the water in the drum which has the highest concentration will raise to a higher level than in the other and this action will 70 in itself tend to cause a flow of water from one drum to the other through the pipes which connect the drums, thus mingling the water and assisting in equalizing the concentration. 75

In the form shown in Figures 6 and 7, the pipe 201 is made to project downwardly through the splash plate 18 and then leads rearwardly for a short distance, and then out into the side of the drum 15. Similarly, 80 the mouth of pipe 211 is beneath the splash plate 18 in drum 15, and passes out through the drum 15 and connects with the drum 14. In each of these cases the entrance to the pipe is placed above the nipple 17 so that 85 some of the water flowing up from the uptake headers 12 will pass into the pipes 201, 211 and from thence into the adjacent drum to enter the circulation thereof.

While I have illustrated the form of my invention shown in Figs. 4, 5, 6 and 7 as applied to two drums only, it will be understood that it may be applied to any number of drums, each of the drums of a boiler, regardless of the number of such drums, being preferably connected to another drum so that water will pass from each drum of a set to another drum of a set. 90

While I have shown my invention applied to a boiler of one definite type, it will be understood that it is applicable to any boiler in which there are a plurality of definite sections in which the possibility of undue concentration in any one of them is possible. 100

I claim:—

1. A steam boiler comprising a plurality of sections, each section having a drum, a plurality of water tubes, downtake and uptake headers connecting the tubes, and nipples connecting the headers respectively with the opposite end of the drum, one of the nipples in each section being connected with a header in another section. 110

2. A steam boiler comprising a plurality of sections, each section having a drum, a plurality of water tubes, downtake and uptake headers connecting the tubes, and nipples connecting the headers respectively with the opposite ends of the drum, one of the downtake nipples in each section being connected with a downtake header in another section. 120

3. A steam boiler comprising a plurality of sections, each section having a drum, a plurality of uptake and downtake headers, nipples, each connecting one of the leaders with one of the ends of the drum, a plurality of water tubes extending between each uptake and downtake header, and a nip- 125

- ple connecting the drum with a header in another section.
4. A steam boiler comprising a plurality of sections, each section having a drum, a plurality of uptake and downtake headers, nipples, each connecting one of the headers with one of the ends of the drum, a plurality of water tubes extending between each uptake and downtake header, and a nipple connecting the drum with a downtake header in another section.
5. A steam boiler comprising a plurality of sections, each section having a drum, a plurality of uptake and downtake headers, nipples, each connecting one of the headers with one of the ends of the drum, a plurality of water tubes extending between each uptake and downtake header, and a connection between each drum and one of the headers in another section. 15

DAVID S. JACOBUS.
